[57] CLAIM

The ornamental design for a "light for attachment to dog", as shown and described.

DESCRIPTION

FIG. 1 is a front perspective view of a light for attachment to dog showing my new design, with the broken line showing for illustrative purposes only and forming no part of the claimed design;

FIG. 2 is an enlarged front elevational view thereof, with the opposite sides being a mirror image; and,

FIG. 3 is a bottom plan view thereof.
